UNITED STATES PATENT OFFICE

HERMAN S. SCHNEIDER, OF CHICAGO, ILLINOIS

DISH WASHING DEVICE

Application filed June 15, 1928. Serial No. 285,543.

My invention relates to dish washing devices, and more particularly to a rotary dish washing device of the power-operated type.

The object of my invention is to provide a device of the kind described, of comparatively simple, rugged construction, convenient for use and efficient in operation.

Another object of my invention is to provide a practical, power-operated dish washing device adapted to effect a substantial saving in labor and in the soap or alkaline solutions employed during the washing process.

Other objects and novel features of the design and construction employed will appear more fully in the hereinafter specification when taken in connection with the accompanying drawings in which

Figure 1 is a longitudinal sectional view, partly in elevation, of an embodiment of my invention.

Figure 2 is a longitudinal sectional view taken on line 2—2 of Figure 3.

Figure 3 is a cross-section taken on line 3—3 of Figure 2.

Figure 4 is an enlarged detailed view in section of the clutch and associated parts.

In the drawings wherein similar characters indicate corresponding parts in the several views, 6 designates a liquid-containing drum of substantially semi-cylindrical configuration, the drum being suitably secured to supporting members 7, 8, having feet 9, and annular flanges 10, the latter of which are engaged by the semi-circumferential wall of the drum in a manner to provide a liquid-tight connection, as best shown in Figure 1. The bottom of the drum 6, is sloping to facilitate the emptying of the drum through the drain cock 11. The supporting members 7, 8, are provided at their midpoint with integral journal bearings 12, 13, in which are secured the stud shafts 14, 15, by set screws 14', 15', respectively. Mounted on the periphery of bearings 12, 13 where they protrude within the drum is a rotatable lid 16, which is adapted to form a cover over the drum when in operation, as shown in Figure 1. The lid 16 is of semi-cylindrical shape and has ends 17, 18, the end 17 being provided with arcuate cut out portions 17' to

admit the journal bearing of the clutch-operated shaft, which will be described hereinafter. As best shown in Figure 3, the revolving lid 16 has a bent edge or lip 19 providing a socket 20, the lip and socket registering with a similar lip 21 and socket 22 formed in the upper edge of the drum 6. It will be seen that when the lid 16 is turned, the registering of the lips 19 and 21 in their respective sockets will prevent further revolution of the lid. I have also placed a hinged hasp 23 on the drum, this hasp being secured to the lid by a wing nut 24.

Within the drum 6 is a hamper or basket 25 which is provided with journal sockets 26, 27. The set screws 28, 29, which are threaded through these journal sockets serve to secure the basket 25 to the fixed shafts 14, 15. As shown in Figures 1 and 2, the basket is also provided with dish-retaining members 30 which are secured to the sides 31, 32, of the hamper 25. These dish retaining members consist of pieces of substantial wire bent to form convolutions which are adapted clampingly to retain plates, saucers, cups, knives, etc. and other items employed in the preparation and serving of meals. By referring to Figure 2 it will be seen that I have provided diagonally positioned wire retainers 33, 34, in which the plates 35, 36, are removably held.

With a view to causing circulation of liquid through the mesh of the wire hamper, I provide an agitator or paddle wheel 37 which has a number of vanes 38 removably secured to radially extending members 39 formed on the periphery of a hub 40, on which latter is a gear 41 secured thereto. The gear 41 meshes with a gear 42 having a flange 43, the flange 43 being fastened to a revolvable sleeve 44 having an integral spiral clutch jaw 45 adapted to be engaged by a coacting spiral jaw clutch member 46 resiliently impelled by a spring 46'; the jaw clutch 46, as best seen in Figure 2, being splined on shaft 47 for a purpose which will be described hereinafter.

The vanes 38 of the agitator wheel 37, as best shown in Figure 3, are configured in a manner to scoop liquid from the bottom of the drum and impel it through the open wire mesh of the basket 25. The vanes, as will

100

- be seen, comprise T-shaped members 48 which are seated in the forks 49 of the radially extending members 39, the T-shaped members being secured by means of bolts and wing nuts 50. When it is desired to replace a vane for any purpose, it will be necessary to remove the wing nuts and withdraw the bolts, after which the T-shaped members 48 may be taken out for removal or repairs, as desired.
- 10 On a bracket 5, secured to an end wall of the drum 6, is a motor 51 coupled to a shaft 52, leading to a housing 52', having a worm 53 meshing with a worm gear 54 mounted on the shaft 47 upon which is rotatably mounted 15 the clutch member 45 secured to the smaller gear 42 also rotatably mounted upon shaft 47 and which meshes with gear 41 on hub 40.
- The function and mode of operation of my device has been in a large measure indicated 20 by the foregoing detailed description, but will become more fully apparent by the following brief description:
- When it is desired to make use of the device, the drum 6 will be partially filled with 25 a soapy or alkaline solution, preferably heated. The dishes are now inserted in the basket 25 which, in the drawings, is provided with the wire retaining members pointed out above, the number of retaining members here- 30 in illustrated being only adequate to set forth their function, since in actual practice I have found it desirable to provide this basket with sufficient wire retainers placed in staggered relation to hold all species of dishes and cutlery. The basket is, of course, retained by the set screws 28, 29, motionless on the shaft, but if desired may be removed by withdrawing the stud shafts 14, 15, after the other set screws 14', 15', have been loosened.
- 40 Assuming the basket to be filled with the required number of dishes, etc. the lid 16 will now be swung to form a complete covering over the drum, as best shown in Figures 1 and 3, the lid being locked during the power operation of the device by a hasp 26 and its co-acting wing nut. The motor 51 will now be set in operation, causing the shaft 52 and consequently the worm 53 to revolve, thereby turning the worm gear, 54, shaft 47, and gear 42, in a counter-clockwise direction, the latter meshing with gear 41 secured to hub 40 of the agitator wheel 37, it being observed that the spring 46' will normally cause the sliding clutch jaw 46 splined on shaft 47, to oper- 45 atively engage its corresponding member 45 on an extension of which the gear 42 is secured.

When it is desired to inspect the contents of basket 25, after the motor has been stopped, 50 the agitator wheel 37 may be revolved in the same direction as that in which the motor has been revolving it, this being effected by means if the slideable double clutch which, as best shown in Figure 2, will be automatically re- 55 leased when the gear 42 is manually turned

in the same direction. I have found this species of clutch to be quite useful, not only for examination of the elements within the drum but also as affording a convenience in removing, for example, a broken dish.

The herein described dish washer, it is to be observed, requires a comparatively small quantity of water or solution. This is in contra-distinction to the many other existing types of dish washing devices which accomplish their function and purpose by the consumption of large quantities of water or solution flowing continually through their jets. I am, therefore, able to effect a substantial saving, not only of water, but that which is more important, the soaps and alkalies which commercial establishments particularly find it desirable to use, with a view to more quickly performing the cleansing operation.

It will be apparent that the device is susceptible of wide modification and change; it being understood that I have illustrated and described merely a preferred form of my invention. Hence I do not confine myself literally to the details as set forth but only insofar as they fall within the scope and spirit of the appended claims.

What I claim is new and desire to secure by Letters Patent is:

1. A device of the kind described comprising a drum, a dish-containing basket in said drum, said drum having an adjustable cover, said basket and cover being removably connected to said drum, an agitator wheel within said drum and rotatably mounted about said basket, a power-operated shaft, drive mechanism operatively connecting said shaft and said agitator wheel, and a releasable one-way clutch operatively mounted in said drive mechanism.
2. A device of the kind described comprising a drum, shafts removably secured to said drum, a basket secured to said shafts, an agitator wheel rotatably mounted upon said shafts, power-operated gear mechanism operatively connected to said agitator wheel, and a releasable one-way clutch operatively connected to said gear mechanism.
3. A dish washing device of the kind described comprising end supporting members, a drum adapted to contain liquid on said end supporting members, a journal socket fastened to one of said end members, a sleeve rotatable in said journal socket and having an integral jaw clutch, a gear secured to said sleeve, a shaft in each of said supporting members, a dish-containing basket secured on said shafts, a lid connected to said drum, an agitator wheel removably mounted on said shafts, a gear secured to the agitator wheel and coacting with said first-mentioned gear, a power-operated shaft rotatably mounted in the said one of the end supporting members, and a spring-impelled clutch member splined

on said power-operated shaft and registering with and engaging said jaw clutch.

4. A dish washing device of the kind described comprising end supporting members, a drum adapted to contain liquid fastened to said end supporting members, a journal socket fastened to one of said end members, a sleeve rotatable in said journal socket, a gear secured to said sleeve, a shaft in each of said supporting members, a dish-containing basket secured on said shafts, a lid connected to said drum, an agitator wheel removably mounted on said shafts, a gear secured to the agitator wheel and coacting with said first-mentioned gear, a power-operated shaft rotatably mounted in the said one of the end supporting members, and a releasable one-way clutch member interposed between said power-operated shaft and said first-mentioned gear.

5. A dish washing device comprising end supporting members, a drum adapted to contain liquid secured to said end supporting members, a shaft in each of said supporting members, a basket mounted upon said shafts, an agitator wheel rotatably mounted upon said shafts and provided with a gear, and power mechanism operatively connected to said gear and adapted to revolve said wheel in one direction including a releasable one-way clutch operatively interposed between said power mechanism and said gear.

In testimony whereof I have signed my name to this specification.

HERMAN S. SCHNEIDER.
